(57) **CLAIM**

The ornamental design for a hand shower support as shown and described.

DESCRIPTION

FIG. 1 is a perspective view of a hand shower support showing our design;

FIG. 2 is a front elevational view;

FIG. 3 is a rear elevational view;

FIG. 4 is a side elevational view;

FIG. 5 is a side elevational view;

FIG. 6 is a top plan view;

FIG. 7 is a bottom plan view; and,

FIG. 8 is an enlarged view of portion 8 in FIG. 1.

The dash-dash broken lines show portions of the hand shower support that form no part of the claimed design. The dash-dot-dash broken lines show the boundary of the enlargement area and form no part of the claimed design.

1 Claim, 8 Drawing Sheets
